HANDLE FOR SLIDING WINDOW

Arthur Mummeney, Hempstead, N.Y., assignor, by
mesne assignments, to Irving Air Chute Co., Inc., Lexington,
Ky., a corporation of New York
Filed July 24, 1958, Ser. No. 750,804
14 Claims. (Cl. 20—52)

The present invention relates to a window having sliding sashes, and in particular to the construction of handles for the sashes which cooperate in a novel manner with the side rails between which the windows slide, to the end that the sashes may be retained in desired adjusted position, may readily be moved to a new position, may be locked in position, and in a preferred embodiment, may be removed from between the rails.

Windows with vertically slideable sashes have long been in common use. A prime requisite of such windows is that the sashes, which are guided in and slide vertically between the side rails of the window frame, should be adjustably positionable in a variety of locations so as to provide for the desired degree of ventilation or access through the window opening. With changes in climatic conditions or for other reasons the positions of the sashes must be readily adjustable, and it is most desirable that said adjustment should require as little manipulation as possible. The optimum mode of adjustment is merely to slide the window to its desired position. With counterbalanced sashes which are more or less frictionally received within the side rails, no particular problem is involved. With uncounterbalanced sashes, however, such as are commonly used in the "aluminum" windows of today, the force of gravity acting on the sashes tends always to move them to their lowermost positions. Means must be provided for preventing this. These means usually comprise catches mounted on the window sash which engage with appropriately shaped structure on the window frame. It is often the case that these catches, which prevent the sash from moving downward, must also be disengaged from the frame when the sash is to be moved upward. This extra manipulative step is a decided drawback.

Means must also be provided for locking the window sashes against unauthorized movement in either direction in order to maintain the security of the interior of the room of which the windows are a part. In conventional windows this locking effect can be accomplished only when all the sashes are fully closed. This, too, represents a disadvantage, since it may be desired to have the windows slightly open during the night to provide for ventilation of the room. It is most desirable if the sashes could be locked in position to provide for such ventilation and at the same time prevent unauthorized entry of intruders from the outside.

Furthermore, and particularly with "aluminum" windows, it is desirable that the individual sashes be removable from the window frame for cleaning and replacement.

In accordance with the present invention the sash, the framework of which is here specifically disclosed as formed of aluminum extrusions and which slides within a frame also formed of aluminum extrusions, is provided with a pair of handles which secure it to the window frame and which cooperate with the window frame, when in a first operative position, to permit the sash to be retained in a selected one of a plurality of adjusted positions, and to be moved in one direction (preferably upwardly) without having to readjust, reposition or manually manipulate the handles in any way. To move the window in the opposite direction (preferably downwardly) one merely need press inwardly on the handles at right angles to the plane of the window. When the handles

2

are located in a second operative position the sash is locked, and cannot be moved either upwardly or downwardly unless the handles are pressed inwardly. Preferably the handles can also be moved to a third operative position in which they become disengaged from the rails, thus permitting the sash to be swung out from the frame or completely removed therefrom. The handles are normally retained in the first operative position above described by reason of a detent engagement between themselves and the sash, but they may be moved to either of their other operative positions by pressing inwardly thereon to disengage the detent.

These results are achieved, in the form here specifically disclosed, by slidably mounting the handles on the sash so that they are movable outwardly toward the side rails of the frame and inwardly away therefrom between operative positions, the handles also having a limited degree of movement in a direction at right angles to the plane of the sash, resilient means being active on the handles to urge them in one direction of that limited degree of movement, preferably outwardly toward the front of the window facing the inside of the room. The handles have portions adapted to extend out laterally from the sashes and be received within appropriate structure on the side rails of the frame, that structure having recesses into which the outwardly extending handle portions are urged by the resilient means. The outwardly extending handle portions have an outer part and an inner part which are differently configured. When one of those parts is received within a recess in the side rail, as will be the case in the first operative position of the handle as above set forth, it will cooperate with that recess, as by means of an abrupt wall engaging an abrupt edge of the recess, to prevent movement of the sash in one direction (preferably downwardly) unless and until the handle is pushed in (toward the rear of the window, as disclosed) against the action of the biasing means, such inward movement of the handle causing the handle part to move out from the recess. The opposite wall of the handle part under discussion will cooperate with the recess, as by having a cam surface formed thereon which engages with the corresponding recess edge, so that when the sash is moved in the opposite direction (upwardly) the handle portion will be cammed inwardly against the action of the resilient means and thus escape from the recess, thereby permitting the sash to be moved upwardly without having to manually manipulate the handle in any way. The second handle part, which is positioned in the side rail recess when the handle is in its second operative position as above described, will cooperate with that recess, as by having abrupt walls on both sides thereof engageable with the correspondingly abrupt edges of the recess, so as to prevent movement of the window in either direction unless and until the handle is pressed inwardly against the action of the resilient means. The handle may have a third operative position in which the handle portion is retracted to a degree sufficient so that it no longer operatively engages its corresponding side rail, thus freeing that portion of the sash to which the handles are attached (usually the lower portion thereof) from the frame and permitting the sash to be swung out or removed from the frame.

Thus a simple and sturdy handle may be inexpensively produced and assembled with the sash, that handle permitting, through manipulation thereof, the selection of a desired condition for the sashes—one in which the sashes may be lifted merely by urging them in that direction, or one in which the sashes may not be moved in any direction unless the handles are appropriately manipulated—an also permitting the sashes to be removed from the window frame whenever that is desired. The sashes may be locked against movement up or down even

when they are not in completely closed position, thus providing for a high degree of security without sacrifice of flexibility in ventilation.

To the accomplishment of the above, and to such other objects as may hereinafter appear, the present invention relates to the construction of a slidable sash window and of handles for the sashes thereof as defined in the appended claims and as described in this specification, taken together with the accompanying drawings, in which:

FIG. 1 is a front elevational view of a window constructed according to the present invention and having three sashes, the handles on each of the sashes being shown in a different operative position;

FIG. 2 is a front elevational view of the window frame;

FIG. 3 is a cross sectional view taken along the line 15 3—3 of FIG. 2;

FIG. 4 is a fragmentary front elevational view showing the cooperation of the handles and side rails when the handles are in their operative position permitting upward movement of the sash;

FIG. 5 is a top plan view of a handle;

FIG. 6 is a side elevational view of the handle with the biasing spring in place;

FIG. 7 is a cross sectional view taken along the line 7—7 of FIG. 5;

FIG. 8 is a cross sectional view taken along the line 8—8 of FIG. 4;

FIG. 9 is a cross sectional view taken along the line 9—9 of FIG. 8;

FIG. 10 is a view similar to FIG. 9 but showing the handle being cammed inwardly as the sash is lifted;

FIG. 11 is a cross sectional view similar to FIG. 8 but showing the handle in a second operative position in which the sash is locked against movement in either direction;

FIG. 12 is a cross sectional view taken along the line 12—12 of FIG. 11;

FIG. 13 is a view similar to FIG. 12 but showing the position which the handle assumes when it is pushed inwardly against the action of the biasing spring; and

FIG. 14 is a cross sectional view taken along the line 14—14 of FIG. 1 and showing the handle in a third operative position in which it is disengaged from the window frame.

The window as here disclosed comprises a frame generally designated A and three sashes generally designated B, C and D vertically slidable within the frame. The frame comprises side rails 2 and 4 and top and bottom rails 6 and 8, each of the rails being formed with three channels 10, 12 and 14 extending rearwardly from the front wall 16 of the frame which is adapted to be directed inwardly into the room. Each of the channels has a front surface *a* and rear surface *b*, and recesses 18 are formed in the front surfaces *a* of the channels 10, 12 and 14 at predetermined positions therealong, these recesses 18 being provided in opposed pairs in the channels in the side rails 2 and 4. The side and top rails 2—8 may conveniently be formed from aluminium extrusions, the recesses 18 thereafter being produced by a suitable machining operation.

Each of the sashes B, C and D are composed of side frame pieces 20 and 22 and top and bottom frame pieces 24 and 26 which carry a central panel. In the sashes B and C this central panel comprises a pane of glass 27, while in the sash D the central panel comprises a screen 28. The sashes B, C and D may all be of substantially the same height, but they differ in width. One of the sashes, here disclosed as the sash B, is the widest and slides between the narrow front walls 30 which define the front of the channels 10. The sash C is somewhat narrower than the sash B so as to slide between the front walls 32 of the channels 12. The sash C is the narrowest of the three sashes and slides between the front walls 34 of the channels 14.

The bottom frame pieces 26 of the sashes B, C and D

are provided with apertures 36 extending inwardly from the sides thereof, those apertures being defined by the rear walls 38, the side walls 40 and the front walls 42 of the frame pieces 26, slots 44 being provided in the front walls 42 which expose but are narrower than the apertures 36. Recesses 46 are formed in the front wall 42 extending upwardly and downwardly from the slots 44.

The handles, generally designated E, are adapted to be received within the apertures 36 so as to be slidable laterally therealong toward and away from the side rails 2 and 4. The depth of the apertures 36 is therefore greater than the thickness of the handles E. Each handle E comprises an elongated body 48 of appropriate structural material such as aluminum the width of which is less than that of the aperture 36 in which it is to be received but greater than that of the slot 44 which exposes the interior of the aperture 36. An intermediate portion of the body 48 may be cut away at 50 to provide a finger opening exposed through the slot 44. A central longitudinal part 52 of the handle is raised from the body 48 and has a width such that it can pass through the slot 44, and it carries a pair of ears 54 which may be received within the recesses 46.

The handle E has an end portion generally designated 56 which is adapted to extend out laterally from the sash frame piece 26 through an end of the aperture 36. The handle portion 56 comprises an outer part 58 and an inner part 60, both disclosed as raised from the body 48 and having a width somewhat less than the width of the recesses 18 in the channels 10, 12 and 14. The outer part 58 has an abrupt lower edge 62 and an inclined or cammed upper edge 64. The part 60 has an abrupt lower edge 66 and an abrupt upper edge 68. The upper and lower edges of the recesses 18 are also abrupt.

Interposed between the handles E and the bottom walls 38 of the apertures 36 is a bowed resilient leaf spring 70 which acts as a resilient biasing means urging the handle E toward the top wall 42 of the aperture 36, the raised portion 52 of the handle E thus moving into the slot 44. One end 72 of the spring 70 may be upbent and received within a recess 74 formed in the undersurface of the handle body 48.

The handles E, together with the springs 70, are inserted into the apertures 36 in the bottom frame pieces 26 of the sashes B, C and D through the open lateral ends of the apertures 36 until they are substantially completely received within those apertures. Tabs 76 (see FIG. 14) may be struck up from the bottom walls 38 to serve as positive stops limiting the laterally inward movement of the handles E. The upper ends of the sashes B, C and D are provided with lugs 78 which may be positioned in the appropriate channels 10, 12 or 14. The sash is then swung into the plane of the frame A, after which the handles E are slid laterally outwardly toward the side rails 2 and 4 until the ears 54 on the handles E come opposite the recesses 46, at which time the action of the spring 70 will cause the ears 54 to snap into the recesses 46. This will arrest the laterally outward movement of the handles E in positions such that 60 the outer handle parts 58, but not the inner handle parts 60, enter the appropriate channels 10, 12 or 14. (See FIGS. 4 and 8, and sash D in FIG. 1.)

When a handle E is in this position the action of the spring 70 will urge it forwardly toward the wall 42 and hence, when the handle part 58 registers with an exposed recess 18 in the front wall of the channel, the spring 70 will urge the handle part 58 into that recess 18 (see FIG. 9). Engagement between the abrupt bottom wall 62 of the handle part 58 with the abrupt bottom edge of the aperture 18 will prevent downward movement of the sash wall unless and until the handle E is moved inwardly in a direction at right angles to the plane of the window and against the action of the spring 70 for a sufficient distance to remove the handle part 58 from the recesses 18 (compare FIG. 13). This may readily be accom-

plished by pressing on that portion of the handle E adjacent the part 58 which is exposed through the slot 44.

However, with the handle E in its operative position shown in FIGS. 4 and 8, if one wishes to raise the sash all that one need do is move it in that direction. As may be seen by comparing FIGS. 9 and 10, when the sash is thus moved the upper inclined camming wall 64 of the handle part 58 engages with the upper edge of the recess 18 and forces the handle E inwardly against the action of the spring 70, thereby removing it from the recesses 18 and permitting the sash to move upwardly.

When it is desired to lock a sash in a desired position, so that it cannot be moved upwardly except when the handles E are appropriately manipulated, the handles are pressed inwardly toward the rear of the window against the action of the spring 70 and then moved laterally outwardly to the position shown in FIG. 11 (and see sash C in FIG. 1), in which position the inner handle part 60 enters the channel 10, 12 or 14 so as to be received within an appropriate recess 18 when the sash is properly vertically positioned. The handle part 60 has upper and lower edges 66 and 68 which are both abrupt, and consequently the handle part 60 will prevent movement of the sash either upwardly or downwardly unless and until the handle E is pressed inwardly against the action of the spring 70 (compare FIGS. 12 and 13).

When the sash is to be unlocked the handles E are engaged in any appropriate manner, as by means of the finger recesses 50, and slid laterally inwardly until the ears 54 snap into the slots 46, there urged by the spring 70. The handles E will then be in their first described operative position in which the sashes may be lifted without having to manipulate the handles.

If one desires to remove a sash from the frame all one need do is press the handles E inwardly against the action of the springs 70 and then move them laterally inwardly to the positions shown in FIG. 14 (and see sash B in FIG. 1), in which the handle end portions 56 are completely disengaged from the channels 10, 12 or 14, after which the sash may be swung outwardly and then pivoted so as to disengage its lugs 78 from the appropriate channels.

The handles E are accessible only from the front of the window, which is directed inwardly into the room of the window forms a part. Consequently, particularly when a three-sash window such as is here disclosed is involved, and where one of the sashes carries a screen 28, the window may be opened and locked at the same time so as to provide an appreciable degree of security against unauthorized entry through the window. This is, of course, of considerable importance for downstairs or ground level bedrooms in private homes. For example, the upper part of the window can be closed by the sash B, and the lower glass pane sash C can be raised to an intermediate position to permit air to pass through the window, both of the sashes then being locked by sliding their respective handles E outwardly. Pressure on the sashes from the outside of the window therefore will be ineffective to cause them to move from their locked positions. In order to prevent a would-be intruder from inserting his hand through the open portion of the window and reaching up to manipulate the handles E, the screen sash D may be moved to completely cover the opening left by the sash C, the screen sash D then being locked in position.

The handles E can be very inexpensively manufactured, as by a die casting operation. They are preferably monolithic in structure, and are hence extremely sturdy and reliable. They are very easily assembled with the window sashes, and when assembled function in a substantially foolproof manner. They provide for a high degree of freedom in manipulation of the windows and, when moved to locked position, reliably perform their locking function.

While but a single embodiment of the present invention

has been here disclosed, it will be apparent that many variations may be made therein, all within the scope of the instant invention as defined in the following claims.

I claim:

- 5 1. In the combination of a window frame having side rails the walls of which define channels extending lengthwise thereof, a window sash mounted on said frame for movement lengthwise of said rails, and a handle on said sash having a portion adapted to extend out laterally therefrom into one of said channels; the improvement which comprises said handle being movable in a first direction laterally relative to said rails between outer and inner positions, said handle having a limited degree of movement in a second direction at right angles to said first direction and from front to rear of said sash between first and second positions, means biasing said handle to said first position, in which first position said handle portion engages a wall of said channel, said channel wall having a recess extending in said second direction in which said handle portion is receivable when said handle is in its first position, said handle portion having an outer part and an inner part, one of said parts having upper and lower edges adapted to engage with the corresponding edges of said recess when said part is received therein and on movement of said part in the direction of the length of said rails, engagement of said edges of said part and said recess preventing escape of said part from said recess when said part is thus moved, at least one of the upper and lower edges of the other of said parts constituting a cam edge which cooperates with the corresponding edge of said recess on movement of said part in the direction of the length of said rail so as to move said handle to its second position, said handle part escaping from said recess when said handle is in said second position, one of said handle parts registering with said recess when said handle is in its inner position and the other of said handle parts registering with said recess when said handle is in its outer position.
- 10 2. The combination of claim 1, in which said handle and said sash are provided with elements interengageable when said handle is in its first position and in one of said inner and outer positions so as to retain said handle in that position, said elements disengaging when said handle is moved to its second position, thereby permitting said handle to be moved to the other of its inner and outer positions.
- 15 3. The combination of claim 1, in which said inner handle part carries said upper and lower edges which prevent escape of said part from said recess, said inner handle part registering with said recess when said handle is in its outer position.
- 20 4. The combination of claim 1, in which said first position of said handle is disposed toward the front of said sash relative to said second position, in which said handle and said sash are provided with elements interengageable when said handle is in its first position and in its inner position to retain said handle in that latter position, said elements disengaging when said handle is moved to its second position, thereby permitting said handle to be moved to its outer position, and in which said inner handle part carries said upper and lower edges which prevent escape of said part from said recess, said inner handle part registering with said recess when said handle is in its outer position.
- 25 5. The combination of claim 1, in which said handle is movable in said first direction to a further inner position in which said handle portion is completely withdrawn from said channel.
- 30 6. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 35 7. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 40 8. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 45 9. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 50 10. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 55 11. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 60 12. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 65 13. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 70 14. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.
- 75 15. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position.

7. The combination of claim 5, in which said handle and said sash are provided with elements interengageable when said handle is in its first position and in its inner position to retain said handle in that latter position, said elements disengaging when said handle is moved to its second position, thereby permitting said handle to be moved to its outer position, and in which said inner handle part carries the edges which prevent escape of said part from said recess, said inner handle part registering with said recess when said handle is in its outer position.

8. A latch and mounting means therefor comprising a horizontal frame piece having an aperture extending inwardly from a side thereof and partially open at the front face thereof, a handle member in said aperture and slideable along the length of said aperture, said handle member also being movable in said aperture between the front and rear faces of said frame piece, means biasing said handle member toward the front face of said frame piece, said handle member being accessible through the open front of said aperture, said handle member having an end portion adapted to extend out from said aperture beyond a side of a sash and comprising an outer part and an inner part, one of said parts comprising a projection with abrupt side edges and the other of said parts comprising a projection with at least one gradually inclined side edge.

9. In the combination of claim 8, projections on a portion of said handle member received within said aperture, said frame piece having recesses communicating with said aperture into which said projections are received under the influence of said biasing means when said handle member is in a predetermined longitudinal position in said aperture.

10. The combination of claim 8, in which the front face opening of said aperture is narrower than said aperture and extends longitudinally for an appreciable distance, and in which said handle member comprises a portion wider than said front face opening which is received in said aperture and a raised narrower portion having a width less than that of the front face opening of said aperture and received within and slideable along said front face opening.

11. In the combination of claim 8, a stop in said aperture engageable with said handle member when the latter has been slid inwardly along said aperture to a position such that its end portion is substantially entirely received within said aperture.

12. A handle member for a window sash or the like comprising an elongated base, a raised narrower portion

extending up from said base and spaced from both sides thereof, a raised wide portion on said base, and an end portion secured to said base, extending out therefrom substantially in the direction of the length thereof, and comprising an outer part and an inner part arranged longitudinally relative to the length of said base, one of said parts having upwardly abrupt side edges and the other of said parts having at least one gradually upwardly inclined side edge.

10 13. In the combination of a window frame having side rails, a window sash mounted on said frame for movement lengthwise of said rails, and a handle on said sash movable in a first direction laterally relative to said rails between inner and outer positions; the improvement which 15 comprises a different portion of said handle operatively engaging said side rail in each of said handle positions, that portion of said handle which engages said side rail in one of said handle positions cooperating with said side rail to prevent manual movement of said sash both 20 upwardly and downwardly, that portion of said handle which engages said side rail in the other of said handle positions cooperating with said side rail to permit manual movement of said sash in at least one of said upward and downward directions.

25 14. The combination of claim 13, in which said handle is also movable in a second direction at right angles to said first direction, movement of said handle in said second direction causing operative disengagement of said handle portion from said side rail.
